STORAGE CONTAINER FOR ICE CUBES
OR THE LIKE

Robert T. Howitt, Leominster, Mass., assignor to Plastic Academy Products Corp., a corporation of Massachusetts

Filed Mar. 11, 1966, Ser. No. 1,414

Term of patent 7 years

(Cl. D67—3)

FIGURE 1 is a perspective view of a storage container for ice cubes or the like showing my new design;

I claim:

The ornamental design for a storage container for ice cubes or the like, as shown and described.
